2,347,180

DIRECTIONAL RADIO BEAM FOR BLIND LANDINGS

Carl-Erik Granqvist, Stockholm, Sweden, assignor to Aga-Baltic Aktiebolag, Stockholm, Sweden, a corporation of Sweden

Application February 14, 1942, Serial No. 430,903
In Sweden January 13, 1941

3 Claims. (Cl. 250—11)

My invention relates to a directional radio beam for blind landing on air-ports.

It has been proposed to arrange dipole antenna systems with a screen, connected to ground, between the two dipole antenna half parts, and to connect alternately one and the other of the two dipole antenna half parts to said screen. The screen extends substantially perpendicular to the longitudinal direction of the dipole antennas. The dipole antenna half parts are each connected with one of the two conductors from the radio frequency generator feeding the transmitter, said generator preferably being of the vacuum tube type.

If the reversal of the earth connection between the two dipole antenna half parts is timed so that one of them is connected to earth as the other is disconnected from earth the alternate signals will have different strengths in all directions but one, viz. the direction of the screen. A transmitter of this kind is described in my U. S. patent application Ser. No. 363,281, filed October 29, 1940, for Directional radio beacon, now Patent No. 2,309,063, granted January 19, 1943. Transmitters of this kind are particularly suitable for indicating a course in the horizontal direction, but they are not quite suitable for indicating a course in vertical direction, as for instance should be the case for blind landing on an air-port. The present invention relates to a modification of the above mentioned type of beacons, especially suitable for indicating a vertically inclined direction as required for blind landing beacons in air-ports.

According to the present invention impedances are connected between one or both of the dipole antenna half parts and ground and are periodically short-circuited in time with the code which is transmitted by means of the antenna system. The impedances are different. Hence the form of the characteristic curve is changed so that the plane in which a constant sound intensity is heard by a listener no longer coincides with the plane of the screen but is inclined to the screen.

Two embodiments of the invention are shown in the annexed drawing, in which 11 and 12 indicate the dipole antenna half parts, preferably identical, which are separated by means of the screen 13. The dipole antenna half parts have a length of substantially one quarter of the wave length of the transmitted signal wave.

The arrangements according to Fig. 1 and Fig. 2 differ in that the screen in the arrangement according to Fig. 1 is less than the critical

length, whereas the screen according to Fig. 2 is greater than the critical length one, the critical length of the screen being that at which the radiation diagram from each of the dipole antenna half parts will intersect the plane of the screen substantially perpendicularly with the other dipole antenna half part grounded and without the herein described impedance elements.

10 With a screen of supercritical length there is obtained from the fed dipole antenna half part, when the other dipole antenna half part is connected to ground, a sacklike characteristic having its major part on the side of the ungrounded antenna half part. If on the other hand the screen has an subcritical length, the sack-like characteristic of the fed antenna part will have its major part on the side of the grounded antenna half part.

15 20 In the arrangement according to Fig. 1 the generator for radio frequency oscillations is indicated at 14. One of its conductors is connected with the lower dipole antenna half part 12 and the other conductor with the screen. The dipole antenna half part 11 is connected to the screen by means of a suitable impedance 15, in parallel with a contact 17, actuated by a code mechanism 16. The arrangement functions in the following way:

25 30 It is first assumed that the contact 17 is closed, so that the dipole antenna half part 11 is connected to the grounded screen. The screening effect of the screen between the two half parts of the dipole is, however, not complete. Hence a capacitive coupling is present between the two half parts, causing the dipole half part 11 to radiate with a voltage which is capacitively transferred from the dipole antenna half part 12. Due to the difference in propagation time of the two waves from the respective antennas the radiation from the dipole antenna half part 11 will be approximately in phase with the radiation from the antenna half part 12 in a direction inclined upwardly from the screen.

35 40 45 On the other hand the two radiations in a direction below the screen will be more than 90° displaced in phase, and thus essentially counteract or extinguish each other. The consequence will be that a radiation diagram will be obtained having the form indicated by the curve 18.

When a moment later the contact 17 is opened, the impedance of the dipole antenna half part 11 to the grounded screen will change, and as a consequence thereof its radiation will have an essentially different character depending upon

the character of the impedance 15. As an example it may be assumed, that the characteristic is changed into the form indicated by the curve 19.

Now it is obvious that a listener who happens to be higher than the indicated flying direction 20, will hear the signal with stronger intensity when the characteristic has the form 18, and with weaker intensity when the characteristic has the form 19, whereas a listener who happens to be lower than the indicated flying direction will hear the signal with stronger intensity when it has the characteristic 19, and with weaker intensity when it has the characteristic 18. If on the other hand the listener happens to be in the indicated flying line he will hear no difference in sound intensity, as both of the characteristics represent the same signal intensity in this direction.

Preferably the code mechanism 16 is arranged to close and open the contact 17 in time with a complement code, for instance in time with the Morse code letters E—T. The pilot may then, by listening to the code, determine if he happens to be higher or lower than the indicated flying direction.

In the arrangement according to Fig. 2 the radio frequency generator is indicated at 21. Its two conductors are connected with the two dipole antenna half parts 11 and 12 respectively. An impedance 22 is connected between the antenna half part 12 and the screen and is coupled in parallel with a contact 24 actuated by a code mechanism 23. The operation of the arrangement is substantially the same as that of the arrangement according to Fig. 1. When the dipole antenna half part 12 is directly connected to earth, the radiation only takes place by means of one of the dipole antenna half parts, but in this case it will be the dipole antenna half part 11 which directs the radiation, as the screen 13 is of such a length that the capacitive transfer between the two dipole antenna half parts is exceedingly small. The diagram of the radiation is indicated 25. When the contact 24 is opened, in addition to the radiation from the antenna half part 11 represented by the diagram 25, a further radiation will take place from the antenna half part 12, which in certain directions cooperates with the radiation 25, but in other directions counteracts this radiation. The radiation diagram for this further radiation will be

substantially dependent upon the impedance 22. It will therefore cause a deformation of the diagram 25, which may for instance be assumed to be in the form indicated by the diagram 26.

5 In this case direction finding takes place in the same manner as with the arrangement according to Fig. 1. The course direction is indicated 27.

Of course the invention is not limited to the 10 embodiments shown in the specification and the drawing, but it may be modified in several manners without departing from the scope thereof. An essential advantage of the arrangements according to this invention is that they are 15 circular symmetrical, so that the flying angle is the same in different azimuth directions. However, if it should be desired to indicate different flying angles in different azimuth directions this may easily be accomplished by arranging the 20 antenna system in a manner suitably inclined in relation to the surface of the earth.

What is claimed:

1. A radio transmitter for blind landing on air-ports, comprising a dipole antenna having 25 two cooperating dipole antenna half parts and a grounded screen therebetween extending in a plane normal to said half parts, one of the dipole antenna half parts being connected with the screen through an impedance, a radio frequency generator energizing said antenna to propagate signals therefrom, short circuiting contacts connected in parallel with the said impedance, and a periodically acting code mechanism actuating said contacts to periodically short circuit said impedance in timed sequence for forming code signals.

2. A radio transmitter as set forth in claim 1 in which the screen has a length which is less than the critical length, and the radio frequency generator is connected to the lower dipole antenna and to the screen, said impedance being connected between the upper antenna half part and the screen.

3. A radio transmitter as set forth in claim 1 in which the screen has a length which is greater than the critical length, and a radio frequency generator is connected to the dipole antenna half parts, said impedance being connected between the lower dipole antenna half part and the screen.
